UNITED STATES PATENT OFFICE.

JOHN J. FITZ GERALD, OF PONTIAC, MICHIGAN.

DESIGN FOR A CLOCK.

49.644.

Specification for Design.

Patented Sept. 12, 1916.

Application filed July 10, 1916. Serial No. 108,480. Term of patent 7 years.

To all whom it may concern:

Be it known that I, JOHN J. FITZ GERALD, a citizen of the United States, residing at Pontiac, in the county of Oakland and State of Michigan, have invented a new, original, and ornamental Design for a Clock, of which the following is a specification, reference being had to the accompanying drawing, forming part thereof.

The figure is a front elevation of a clock, showing my new design.

I claim:

The ornamental design for a clock, as shown.

JOHN J. FITZ GERALD.

Witnesses:

JAMES H. LYNCH,
CATHERINE F. LYNCH.
